Primary Examiner — Ruth McInroy

(57) **CLAIM**

The ornamental design for a squeegee nozzle, as shown and described.

DESCRIPTION

FIG. 1 is a perspective view of a squeegee nozzle showing my new design;

FIG. 2 is a top, front and side perspective view thereof;

FIG. 3 is a front elevation view thereof;

FIG. 4 is an end elevation view thereof, the opposite side being a mirror image;

FIG. 5 is a top plan view thereof; and,

FIG. 6 is a bottom plan view thereof.

The details shown in broken lines form no part of the claimed design.
